A. B. HORNE

DEVICE FOR MARKING GOLF BALLS

Filed Dec. 19, 1922

INVENTOR.
Archibald B. Horne.

BY

Harry W. Brown.
ATTORNEY.

UNITED STATES PATENT OFFICE.

ARCHIBALD B. HORNE, OF SPRINGFIELD, MASSACHUSETTS.

DEVICE FOR MARKING GOLF BALLS.

Application filed December 19, 1922. Serial No. 607,917.

To all whom it may concern:

Be it known that I, ARCHIBALD B. HORNE, a citizen of the United States of America, residing at Springfield, county of Hampden, Commonwealth of Massachusetts, have invented certain new and useful Improvements in Devices for Marking Golf Balls, of which the following is a specification.

This invention relates to improvements 10 in devices for marking golf balls so that the name of the owner of the ball may be permanently recorded on the outer surface of the ball.

Heretofore, it has been a common practice to place on the ball only the initials 15 of the owner of the ball. The present invention is for the purpose of impressing the full name of the owner by employing changeable or removable type; the type being provided with means for attaching and securing the same to a flexible band, and by constricting the band and the type about the ball the type is forced against the outer casing of the golf ball, it being understood 20 that the type is first inked or if desired heated to a suitable temperature, whereby the casing is partially softened, so that a distinct impression may be made in the outer surface.

30 Referring to the drawings which form a part of the specification—

Fig. 1 is a side elevational view showing the complete device and the manner of using the same to impress the name on the ball.

35 Fig. 2 is a plan view of the flexible band to which the type is attached.

Fig. 3 is a perspective view of one of the type blocks.

40 Fig. 4 is a view showing the manner of placing the type block on the band, or strip, of flexible material before it is attached thereto, and

45 Fig. 5 is a view showing the manner of securing the type block to the band when it is to be used.

Referring to the drawings in detail:

1 designates the usual golf ball which is formed with an outer shell or casing of gutta percha, or hardened rubber and having the usual depressions or recesses in its outer surface as indicated at 2. 3 is the strip of flexible material, as steel which is formed with a series of openings 4. In the ends of this strip are formed the eyes

5 and 6. 7 designates a suitable handle having pins 8 for receiving the eyes 5 and 6. 9 designates one of the type blocks which is formed with the upwardly projecting side edges 10 and 11, and also an upwardly extending cylindrical projection 12 which is designed to enter one of the openings 4 of the strip 3. The flanges 10 and 11 serve to form a channel, or grooved portion in the top of the type block; the width of this channel being substantially equal to the width of the strip of metal 3, as shown. When the part 12 is inserted in one of the openings 4, the flanges will project above the upper surface of the strip 3. They are now bent 70 or folded downward against the upper surface of the strip or band 3, as shown in Fig. 5 for securing the block to the strip. The part 13 of the type blocks 9 indicates the type portion that carries the letter of the block and forms the depression below the outer surface of the golf ball, as indicated in Fig. 1 at 13'.

By using a band, as shown, it is possible to embed type blocks bearing the whole 80 name of the owner, and by using blocks of different sizes and bands of different lengths as many letters or symbols may be impressed on the ball as desired.

The permanent impression produced by 85 the type blocks on the outer surface of the ball is indicated in Fig. 1 at 14.

The band with the removable letters permits the impressions to be made on the ball substantially throughout the entire circumference of the ball, so that the whole 90 name of the owner of the ball may be impressed.

What I claim is:

1. In combination, a device for forming 95 impressions on the outer surface of a golf ball, a member flexible throughout its length and formed with a series or plurality of openings therein, said openings being for the purpose of removably attaching individual impression forming devices for building up the full name of the owner when impressed on the ball and designed to be attached to the said flexible member at different portions of its length commensurate with the length of the name to be impressed, means for constricting the member uniformly throughout substantially its 100 105

- length to force the devices into the outer surface of the ball, as described, whereby the full name of the owner of the ball will appear thereon.
5. A device for marking golf balls comprising, in combination, with a flexible member of means for attaching a plurality of removable type blocks to the member comprising openings in the flexible member, a part on the blocks for entering the openings and bendable parts on the blocks for engaging the member, and means for constricting the member about the ball for forcing the type blocks against the ball to be marked.
10. A device for marking golf balls comprising, in combination, with a flexible member formed with openings therein, type bearing blocks having parts for entering the openings, and projecting portions on the blocks for securing the same to the member, a handle member attached to the member for bending it into a circular form and for constricting its diameter about the ball to be marked when the handle is operated, whereby the blocks will be forced against the ball.
15. A marking device for producing impressions in the outer surface of a golf ball, or the like, and comprising in combination, an elastic band, means for attaching changeable letter bearing blocks thereto, a handle, the ends of the band each being pivotally connected thereto at spaced points along the handle for bending the band into a circular form and for constricting the band when the handle is operated for forcing the bearing blocks against the ball.
20. A device for marking golf balls comprising in combination with a strip of bendable material, type blocks, devices for attaching the blocks thereto comprising projections on the blocks to form a channel to receive the strip, said projections being bendable and serving to align the type blocks with relation to each other.

ARCHIBALD B. HORNE.
